(No Model.)

D. A. SCHUTT.
FUSE PLUG.

No. 594,908.

Patented Dec. 7, 1897.

UNITED STATES PATENT OFFICE.

DUNY A. SCHUTT, OF PERU, INDIANA, ASSIGNOR TO THE PERU ELECTRIC MANUFACTURING COMPANY, OF SAME PLACE.

FUSE-PLUG.

SPECIFICATION forming part of Letters Patent No. 594,908, dated December 7, 1897.

Application filed April 16, 1897. Serial No. 632,438. (No model.)

To all whom it may concern:

Be it known that I, DUNY A. SCHUTT, a citizen of the United States, residing at Peru, in the county of Miami and State of Indiana, have invented or discovered a new and useful Improvement in Fuse-Plugs, of which the following is a full, clear, and exact description, reference being had to the accompanying drawings, forming part of this application, in which—

Figure 1 represents a portion of a circuit-block equipped with my improved fuse-plug, one of the plugs having been removed. Fig. 2 is a longitudinal section taken on the line 15 II II of Fig. 1. Fig. 3 is a view of the plug in side elevation. Fig. 4 is a top plan view with the cover removed. Fig. 5 is a bottom view.

My device consists of a new and useful improvement in fuse-plugs for use in a single, double, or three wire system of main and branches, and is designed to be used as a protection to lamps on overloaded wires. It is constructed in such a manner that it may be 25 removed from the block and replaced by a lamp, if desired.

Referring to the block A, made of porcelain or other suitable insulating material, the terminals of the circuit consist of a central upwardly-extending threaded post 2 and a surrounding ring 3, each having extensions suitably secured to the base and provided with binding-screws 4.

The fuse-plug consists of a base 5, of porcelain, provided with an upwardly-extending flange 6, within which rests the cap 7. At its bottom the base 5 is provided with two countersunk contacting segments 8 8', extending out to a common level and designed 35 to bear evenly on the ring 3 when the plug is in position, the segment 8 being retained by a screw 9, leading through the base and securing together the segment and an upper terminal plate 10, provided with a binding-screw 11. The center of the base is cored out and a central hollow stud 12 is inserted, enlarged at the bottom and internally screw-threaded to engage the post 2, the upper end passing through a terminal plate 13 and riveted over, thereby making a good electrical connection. The stud is tapped at the top,

and a screw 14, inserted therein, serves to hold the cap in position. The terminal plate 13 is provided with a binding-screw 15, and between the two terminals, secured by the screws 55 11 and 15, is located the fuse 16, thereby establishing a circuit. A suitable groove 17 is made in the top of the base to receive the fuse. Air ducts or slots 18 are provided in the base, and similar holes 19 in the cap, for the purpose of giving air circulation and to allow gas to escape in case of burning of the fuse. The cap also serves to prevent the escape of sparks in case of the burning of the fuse.

The edge of the fuse-plug is preferably 65 knurled, as at 20, so as to provide a secure means for grasping it in the fingers when inserting.

The advantages of compactness, simplicity, and utility will commend my improved fuse-plug to those familiar with the art, as it is applicable to a wide variety of use.

What I claim is—

1. A fuse-plug consisting of a base of insulating material, a center metallic post provided with a fuse connection at the top and internally threaded in its base, a metallic contact in the side of the base with a connecting-screw extending through to the top and provided with a fuse connection, and a fuse attached to such connection, substantially as set forth.

2. A fuse-plug consisting of a base of insulating material, a center metallic post provided with a fuse connection at the top and 85 internally threaded in its base, a metallic contact in the side of the base with a connecting-screw extending through to the top and provided with a fuse connection, and a fuse attached to such connection, with a cap of insulating material secured upon the top of the base, substantially as set forth.

3. A fuse-plug consisting of a base of insulating material, a center metallic post provided with a fuse connection at the top and 95 internally threaded at its base, a metallic contact in the side of the base with a connecting-screw extending through to the top and provided with a fuse connection, a similar oppositely-located bearing-plate, a depressed 100 annular groove in the top of the base, a fuse located therein and attached to the fuse con-

nections, air-vents through the side of the base, and a cap of insulating material secured upon the top of the base by a screw tapped into the center post, and air-vent passages through the cap, substantially as set forth.

4. In combination with the electric terminals of a circuit-block, a fuse-plug consisting of a base of insulating material, a center metallic post provided with a fuse connection at the top and internally threaded in its base, a metallic contact in the side of the base with a connecting-screw extending through to the top and provided with a fuse connection, and a fuse attached to such connection, with a cap of insulating material secured upon the top of the base substantially as set forth.

15 5. In combination with a metallic threaded post forming an electrical terminal and an

encircling detached metallic ring forming the other terminal; a fuse-plug consisting of a 20 base of insulating material, a center metallic post provided with a fuse connection at the top and internally threaded in its base, a metallic contact in the side of the base with a connecting-screw extending through to the 25 top and provided with a fuse connection, and a fuse attached to such connection, with a cap of insulating material secured upon the top of the base, substantially as set forth.

In testimony whereof I have hereunto set 30 my hand this 27th day of January, 1897.

DUNY A. SCHUTT.
